UNITED STATES PATENT OFFICE.

THEODORE HAVILAND, OF AMBAZAC, FRANCE.

DESIGN FOR A COVERED DISH.

SPECIFICATION forming part of Design No. 23,774, dated November 6, 1894.

Application filed October 12, 1894. Serial No. 525,728. Term of patent 7 years.

To all whom it may concern:

Be it known that I, THEODORE HAVILAND, a citizen of the United States, residing at Ambazac, in the Department of Haute-Vienne and 5 Republic of France, have invented and produced a new and original Design for Dishes; and I do hereby declare the following to be a full, clear, and exact description of the same, reference being had to the accompanying 10 drawings, forming a part thereof.

The principal feature of my design consists in a covered dish having a series of four flutings proceeding at regular intervals from the upper edge of the dish and the outer edge of 15 the cover losing themselves in the body of the dish and cover. The handles are made to simulate cherry wood having bunches of cherries and leaves bound to it by ribbon.

Figure 1 represents a side view of the dish, and Fig. 2 a face view of the cover. 20

In Figs. 1 and 2 the flutings are represented by A. These speedily lose themselves in the main portion of the dish.

The handles B are made to represent cherry-wood having attached to them, by 25 means of a ribbon, a twig or small branch of leaves and cherries.

What I claim is--

The design for dishes substantially as herein shown and described. 30

In testimony whereof I affix my signature in presence of two witnesses.

THEODORE HAVILAND.

Witnesses:

EUG. PAPAND,
ARNAUD ANDRIEUX.
